EXPLOSION RESISTING LIGHTING FIXTURE

Harold P. Hastings, Syracuse, N. Y., assignor to
Crouse-Hinds Company, Syracuse, N. Y., a corporation of New York

Application January 19, 1934, Serial No. 707,293

9 Claims. (Cl. 240—11.2)

This invention relates to lighting units of the explosion resisting type, particularly intended for use in hazardous places, where there is the probability of explosion, if the electrical circuit is made 5 or broken in the atmosphere of the location.

The invention has for an object an explosion 10 resisting lighting unit provided with flame tight joints, the construction being of such nature that the efficiency of these joints will not be impaired through ordinary use of the lighting unit.

The invention has for a further object the provision of means for detachably supporting the lamp receptacle in the body of the unit in such manner that the lamp compartment of the unit 15 is effectively sealed.

The invention has for a further object the provision of means for maintaining an effective flame tight joint between the glass globe and the body of the unit and at the same time permitting relamping of the unit without the necessity of skilled labor or any particular tools.

A further and important object of this invention is the provision of means for securing the globe to the globe support in flame tight relationship thereto, and also to provide for expansion and contraction of the globe without effecting the joint.

With the above objects in mind, the invention possesses further novelty in that its structure is 30 such that the unit can be made in the smaller sizes and can be used as an explosion resisting hand lamp, if desired.

Further objects will appear as the description 35 proceeds.

The invention consists in the novel features and in the combinations and constructions herein-after set forth and claimed.

In describing this invention, reference is had 40 to the accompanying drawings in which like characters designate corresponding parts in all the views.

Figure 1 is a sectional view of the unit, partly in elevation, the unit in this instance being provided with a handle for hand lamp use.

Figure 2 is a sectional view of the unit provided 45 with means for attaching the same to an electric conduit system.

The invention comprises generally a body, a lamp receptacle support detachably secured in the body in such manner as to provide a flame tight joint between the support and the body, a globe support detachably secured to the body and means carried by the globe support for detachably securing the globe in the support in flame

tight relationship thereto and a guard separately secured to the support.

As here shown, the body comprises a casting 10 bell shaped in general form and being provided with an internally threaded bore 11. The mouth or open end of the body 10 is threaded externally at 12. 13 designates the receptacle support and is, as here shown, provided with a depending flange 14 and an upwardly extending annular flange 15, the flange 14 being threaded externally 10 and the threads being complementary to those of the bore 11 of the body, whereby the support may be threaded into the body.

A receptacle 16 is secured to the support 13 in any suitable manner, as by screws 17, the support 15 13 being provided with passages 18 to permit the service wires to be connected to the socket or lamp receptacle 16. The upwardly extending flange 15 provides a well which is filled with suitable sealing compound, after the receptacle 16 20 has been properly wired. The externally threaded flange 14 provides a flame tight joint between the support 13 and the body 10 and in conjunction with the sealing compound within the flange 15 forms an effective seal between the lamp compartment of the unit and the upper compartment 25 through which the service wires enter the unit. It will be understood by those skilled in the art that a flame tight joint is a joint which while possibly permitting the passage of gases will cool 30 any ignited gases below the ignition point so that when the gases escape from the unit, there is no likelihood of igniting the inflammable gases in the atmosphere in which the unit is being used.

The support 13 is secured in the body against 35 becoming loosened on account of vibration or otherwise by means of the set screw 19 threading through a boss formed on the upper side of the support, the end of the screw coating with the inner wall of the body, as shown in the drawings. It is to be noted that in the event the receptacle 16, with the wires 37, 31 connected thereto, becomes in any way defective or damaged it may be readily removed from the body together with the support 13 by backing out the set screw 40 19 and unscrewing the support 13 from the body.

As shown in Figure 1, the upper end of the body is truncated and provided with an opening 20 formed in the inwardly extending flange 21. One half, as 22, of the cable clamp is formed integral 50 with the flange 21, the other portion 23 of the clamp being operated by the screws 24. The integral portion 22 of the clamp is provided with a grounding screw 25 to which the grounding conductor of the cable 26 is secured. In this in- 55

stance, where the unit is used as an explosion resisting hand lamp, a handle 27 of rubber or other suitable heat insulating material, is secured to the upper end of the body. As here shown, the handle is provided with a radially extending flange 28 which is secured to the flange 21 by screws 29, the handle forming a closure for the opening 20. The outer end of the handle is provided with a suitable vapor tight bushing 10 and cable clamp 30. This unit may be wired by slipping the handle 27 back on the cable 26, passing the end of the cable through the opening 20 in the body 10, securing the ends of the conductors 31 to the receptacle 16. In lighting units 15 of this type, that is, explosion resisting type, the service wires or leads are generally soldered or permanently secured to the terminals in the lamp receptacle. This is to avoid any possibility of loose connections. After the conductors 31 have 20 been properly secured to the receptacle 16, the receptacle is secured to the support 13 and the support screwed into the body. The ground conductor 32 may then be secured under the screw 25 and the handle 27 secured to the flange 21 25 and the bushing 30 tightened.

Referring to Figure 2 of the drawings, the upper end of the housing is provided with a threaded passage 35 to receive the threaded end of a conduit enclosing the service wires. An opening is provided in one side of the body adjacent its upper end and a closure or plug 36 threaded into the opening. In wiring this unit, the leads 37 from the receptacle 16 and the service wires, not shown, are brought out through the side opening in the housing, properly connected and returned through the opening into the upper chamber of the body. If it becomes necessary to replace the receptacle 16 in this unit, the leads 37 are disconnected from the service wires and the 40 receptacle support 13 is unscrewed from the body. In this unit, and as a general rule, in the hand-lamp unit shown in Figure 1, the receptacle 16 is provided with leads, and the receptacle is secured to the support and the sealing compound run 45 into the well above the support at the factory, rendering it only necessary for the unskilled worker in charge of the units to unscrew the support 13, if necessary to replace the receptacle, and to again screw into the support and receptacle, thus preventing the possibility of rendering the 50 unit ineffective for the purpose for which it was intended, by destroying the seals of the lamp compartment.

The globe 40 of the fixture which defines the 55 lower portion of the lamp compartment is carried by a globe support 41 which is detachably secured to the lower or open end of the housing 10. As here shown, the support 41 is cylindrical and provided with an inwardly extending flange 42 at its lower end, the cylindrical portion being internally threaded, and the threads being complementary to the externally threaded portion 12 of the body 10. The support 41 also carries a guard 43 which is here shown as detachably secured to the support by means of screws 44, although, obviously, the support 41 and the guard 43 may be formed integral. The globe 40 is provided with the usual outwardly extending radial flange 45 which seats upon the gasket 46 which 60 is usually of lead or suitable resilient metallic material. The flange 45 of the globe is somewhat less in diameter than the bore of the support 41 and extends upwardly and inwardly, providing a space 47 which is filled with a suitable sealing compound, preferably a compound which will

remain plastic at ordinary temperatures. An externally threaded ring or washer 48 is screwed into the support 41 and seats against the sealing compound. It will be observed that this structure secures the globe to the globe support in such manner as to prevent the escape of any ignited gases from within the globe, and at the same time permits ready removal of the globe from the support if the necessity arises, and also permits expansion and contraction of the outer 10 or open end of the globe. Inasmuch as this unit is totally enclosed, and particularly in units of the smaller size as here shown, the lamp produces an appreciable amount of heat which results in considerable expansion of the globe 40. 15 Inasmuch as these units must withstand a minimum amount of pressure, usually five hundred pounds per square inch, it is very important that the glass globes are not placed under an initial strain as they would be materially weakened. A 20 clearance is usually provided between the gasket or washer 46 and the bore of the globe support, or the periphery of the globe. When the temperature of the globe rises, the upper end including the flange 45 is permitted to expand on account of the sealing compound 47, and as the globe cools off it contracts and the flame tight joint is still established by the plastic compound. 25

A screw 49 is carried by the body and arranged to form a lock to prevent unintentional removal 30 of the support 41 from the body. As shown in Figure 1, the guard is provided with a suitable hook 50 to permit the unit to be suspended from the outer end, and in Figure 2, a shade 51 may be provided, which is secured to the globe support 41, and as shown, is clamped between the guard 43 and the support 41. It will be observed that these units may be relamped by simply loosening the screw 49 and unscrewing the support or globe and guard unit from the body without, in any manner, affecting the joint between the globe and the globe support. However, while the globe and guard unit are secured to the body, it is impossible to remove the globe from the globe support. 45

The arrangement of this structure and the structure of the receptacle support is to provide a means, whereby the fixture may be maintained by an unskilled operator without disturbing the flame tight joint of the unit, which requires some 50 skill, or at least some appreciation of its value. The globe and support are assembled at the factory and in the event the globe becomes damaged, a new globe unit is provided, permitting the damaged unit to be returned to the factory for re- 55 conditioning by proper persons.

What I claim is:

1. An explosion resisting lighting unit including a body having an internally threaded bore, and an externally threaded annular flange, a 60 receptacle support provided with external threads complementary to the threads in the body, a receptacle carried by said support, a globe and guard unit provided with internal threads complementary to the external threads on the annular flange, a globe and a guard carried by said unit, and a handle detachably secured to the opposite end of the body.

2. An explosion resisting lighting unit including a body open at its ends and having an internally threaded bore, a receptacle support threaded into said bore, and a receptacle carried by the receptacle support, a globe support detachably secured to one end of the body, a globe carried by the globe support, and means for de- 70 75

- tachably securing the globe in said support and forming a flame tight joint between the globe and the support, and a handle secured to the opposite end of the body and forming a closure therefor.
5. An explosion proof lighting unit comprising a body, a receptacle support, means for detachably securing said support in the body, a flame tight joint between the body and the support, a globe support, a globe carried by the support and self-contained therewith, a flame proof joint between the globe and the globe support including an expandable and contractile plastic packing ring between the globe and its support and capable of expanding and contracting and maintaining the joint during different degrees of temperature, and means for detachably securing the globe support to the body and forming a flame proof joint between the globe support and the body.
4. An explosion proof lighting unit comprising a body, a receptacle support, means for detachably securing said support in the body, a flame tight joint between the body and the support, a globe support, a globe carried by the support and self-contained therewith, a flame tight joint between the globe and the globe support including an expandable and contractile packing ring and capable of expanding and contracting and maintaining the joint during different degrees of temperature, the globe having an annular bead tapering toward the inner end of the globe forming a space V-shaped in cross section between the bead and the globe support, the expandable and contractile packing filling said V-shaped space, and means for detachably securing the globe support to the body and forming a flame proof joint between the globe support and the body.
5. An explosion proof lighting unit comprising a body, a receptacle support, means for detachably securing said support in the body, a flame tight joint between the body and the support, a globe support, a globe carried by the support and self-contained therewith, a flame tight joint between the globe and the globe support including a plastic expandable and contractile packing ring between the globe and its support and capable of expanding and contracting and maintaining the joint during different degrees of temperature, the globe having an annular bead tapering toward the inner end of the globe forming a space V-shaped in cross section between the bead and the globe support, the expandable and contractile packing filling said V-shaped space, resilient means for retaining the expandable and contractile packing in said space, and means for detachably securing the globe support to the body and forming a flame proof joint between the globe support and the body.
6. An explosion proof lighting unit comprising a body, a receptacle support, means for detachably securing said support in the body, a flame tight joint between the body and the support, a globe support, a globe carried by the support and self-contained therewith, a flame tight joint between the globe and the globe support including an expandable and contractile packing ring between the globe and its support and capable of expanding and contracting and maintaining the joint during different degrees of temperature, the globe forming a space V-shaped in cross section between the bead and the globe support, the expandable and contractile packing filling said V-shaped space, a resilient metallic washer between the globe and its support and arranged to cover said V-shaped space and arranged to permit radial expanding and contracting movements of the globe and retain the expandable and contractile packing in said space, and means for detachably securing the globe support to the body and forming a flame proof joint between the globe support and the body.
7. An explosion resisting lighting unit comprising a bell shaped body having an internally threaded bore, a receptacle support threaded in said bore and dividing the body into a service compartment and a lamp compartment, said support being provided on one side with a well to receive sealing compound, and a receptacle mounted on the other side of said support and extending into the lamp compartment, and a globe and guard unit detachably secured to the body.
8. An explosion resisting lighting unit comprising a bell shaped body open at each end and having an internally threaded bore adjacent the large end, a receptacle support threading into said bore and dividing the body into a service compartment, and a lamp compartment, a receptacle mounted on said support and extending into the lamp compartment and being provided with a well for receiving sealing compound, a globe and guard unit detachably secured to the large end of the body, the smaller end of the body being provided with a cable grip, and a handle detachably secured to the smaller end of the body and forming a closure for the opening therein.
9. An explosion resisting lighting unit comprising a body having an internally threaded bore, a receptacle support threaded in said bore and dividing the body into a service compartment and a lamp compartment, and effecting a flame tight seal between said compartments, a lamp receptacle mounted on one side of said support and extending into the lamp compartment, and a globe and guard unit detachably secured to the body.

HAROLD P. HASTINGS.
